(57) **CLAIM**

The ornamental design of an electrical logic element with relief symbol, as shown and described.

DESCRIPTION

FIG. 1 is a top perspective view of an electrical logic element with relief symbol showing my new design and showing one of the components in a first position;

FIG. 2 is a top perspective view thereof showing one of the components in a second position;

FIG. 3 is a top perspective view thereof showing the components in a third position;

FIG. 4 is a side perspective view thereof showing the components in the third position;

FIG. 5 is a side perspective view thereof showing the components in a different position;

FIG. 6 is a top perspective view thereof showing the components in yet a further different position;

FIG. 7 is a partially exploded bottom perspective view; and,

FIG. 8 is a fully exploded bottom perspective view.
